WITNESS:

UNITED STATES PATENT OFFICE.

WILLIAM CHARLES HERBERT, OF BROOKLYN, NEW YORK.

GAS HEATER.

1,404,151.

Specification of Letters Patent. Patented Jan. 17, 1922.

Application filed February 21, 1920. Serial No. 360,427.

To all whom it may concern:

Be it known that I, WILLIAM C. HERBERT, a citizen of the United States, residing at Brooklyn, in the County of Kings and State 5 of New York, have invented new and useful Improvements in Gas Heaters, of which the following is a specification.

This invention relates to gas stoves and has for its primary object the provision of 10 an improved burner construction which will permit of complete combustion of the gas and enable the stove to be economically operated.

Another object of the invention is to provide 15 a device of the above described character which will be simple of construction, strong and durable, and one in which several novel features of construction are combined so as to permit heat of great intensity to be 20 produced with an elimination of noxious gases.

With the above and other objects in view 25 which will appear as the nature of the invention is better understood, the same consists in the improved construction and novel arrangements of parts which will herein-after be fully described and particularly pointed out in the claims.

In the accompanying drawings has been 30 illustrated a single and preferred form of the invention, it being, however, understood that no limitations are necessarily made to the precise structural details therein exhibited, but that changes, alterations and modifications within the scope of the claims may 35 be resorted to when desired.

Figure 1 is a longitudinal section through the stove.

Figure 2 is a section taken on the line 2—2 40 of Figure 1.

Figure 3 is a view similar to Figure 1 showing a slightly modified form of the invention.

Figure 4 is a section taken on the line 4—4 45 of Figure 3.

Figure 5 is a section taken on the line 5—5 of Figure 4.

In carrying the invention into practice, use is made of a casing 10 or outer shell 50 which can be constructed of foraminated sheet material, the said casing closed at its top by a cap 11. At the base, the casing is provided with a plate 12 flanged at 13 beyond the sides of said casing or shell and, 55 as illustrated, said flange has secured thereto

suitable supporting legs 14 which operate to hold the base of the casing spaced from the floor or other support upon which the stove is mounted. The base plate 12 is provided with a relatively large draft opening 15 60 which opens into the casing beneath the burner 16.

Said burner is in the form of a perforated pipe, the same extending from one end of the casing 10 to the other end thereof. One 65 end of the pipe is closed by a cap 17. The other end is extended through the adjacent end wall of the casing and it is connected with a supply pipe 18 by means of which illuminating gas may be delivered to the 70 burner. The pipe 18 is preferably provided with an air mixer, the same conventionally illustrated at 19 and may be of any well known construction.

Above the burner is a baffle member 20 75 which is flanged at its sides at 21—21. Said baffle is mounted upon an adjustable spring bracket 22 and connected with the bracket is an arm 23 adapted to co-act with one of the perforations in the casing 10 so as to 80 hold the bracket relatively fixed in any one of a plurality of positions. This construction is such that an air space or chamber is defined by the walls of the baffle member and an area of the space can be regulated 85 so as to permit a proper volume of air to be mixed with the gas and thereby insure proper combustion and production of a blue flame. The perforations 24 in the burner 16 are preferably arranged at an angle of 45 90 degrees or approximately so. The baffle member has its top wall directly overlying the burner so that as the gas escapes from the perforations 24 it is made to impinge against the under surface of the top wall of 95 the baffle member, the gas taking the course illustrated by the dotted line A. It then rebounds and takes the course indicated by the dotted line B and it impinges against the inner face of the adjacent flange 21 of 100 said baffle member. Through this arrangement, and from the fact that the baffle member is adjustable so that the air space above the burner can be regulated, it obviously follows that perfect combustion results and 105 that a blue flame will be produced at the burner. The baffle opens downward and spaced from the baffle and curved from a point slightly below the burner to a point to the top of the casing 10 is a deflector 25 110

which operates to cause the heat to be distributed from the front wall 26 of the casing.

The construction above described is such that in some instances I find that the mixer 19 can be entirely eliminated and that the baffle member acts as more than a substantial substitute therefor. By regulating the amount of air in proportion to the volume 10 of gas, directly at the burner, the flame is uniformly blue and a mixture of air and gas is provided for which will enable one to operate the stove economically.

In the form shown in Figures 3 to 5 inclusive, the baffle member 26 is of cruciform shape and the same overlies a burner 27 of corresponding formation. In this instance, the burner has each of its branches provided with a double row of perforations 28. The 20 baffle is fixedly positioned with respect to the perforations. The said baffle is also arranged so that both side flanges 29—29 are utilized for the impingement of the gas thereagainst. This construction provides a 25 combustion chamber above the burner, and the products of combustion are retarded by the action of the baffle by striking the main portion of the plate and being deflected to the side plates 29 for distribution through- 30 out the portions 30 and 31 of the chamber formed by this baffle, for thorough mixture with oxygen so that an effective combustion chamber is provided. The gas, as it leaves the perforations 28 takes the same course 35 with respect to the baffle member as previously referred to.

What is claimed as new is:—

1. The combination with a gas burner, of a baffle comprising an inverted substantially 40 U-shaped member arranged above and partly embracing the burner and designed to form a combustion chamber and means for adjusting the U-shaped member with respect to the burner.

2. The combination with a gas stove and 45 a burner therefor, of an imperforate member arranged above the burner and designed to form a combustion chamber, means disposed to one side of the burner for supporting the latter upon the casing of the stove and means whereby the supporting means 50 may be moved to adjust the member with respect to the burner.

3. The combination with a gas stove and 55 a burner therefor, of an imperforate member arranged above the burner and designed to form a combustion chamber, an arm having one end connected to one side edge of the imperforate member and the other end secured to the casing of the stove and means 60 whereby the arm may be moved to adjust the member with respect to the burner.

4. The combination with a gas stove and 65 a burner therefor, of an imperforate member arranged above the burner and designed to form a combustion chamber, an arm having one end connected to one side edge of the imperforate member and the other end secured to the casing of the stove and means 70 connected to the arm and co-acting with the casing of the stove, whereby the arm may be moved to adjust the member with respect to the burner.

5. A gas heater comprising a casing having perforated walls, a longitudinally extending burner located therein, a member positioned above the burner and shaped to partly embrace the latter to provide a combustion chamber, a baffle wall spaced above and to one side of the chamber to provide 80 a passage between said chamber and baffle wall and means whereby the member may be adjusted relatively to the burner to regulate the area of combustion and maintain substantially the same passage space. 85

In testimony whereof I have affixed my signature.

WILLIAM CHAS. HERBERT.
